UNITED STATES PATENT OFFICE

126,706

DESIGN FOR A BUMPER FOR BALL ROLLING GAME DEVICE

Frank G. Nicolaus, Chicago, Ill., assignor to Raymond T. Moloney, Chicago, Ill.

Application February 17, 1941, Serial No. 99,043

Term of patent 7 years

To all whom it may concern:

Be it known that I, Frank G. Nicolaus, a citizen of the United States and resident of Chicago, county of Cook, State of Illinois, have invented a new, original, and ornamental Design for a Bumper for Ball Rolling Game Device, of which the following is a specification, reference being had to the accompanying drawing, forming part thereof, and in which:

Fig. 1 is a top plan view of a bumper for ball rolling game device showing my new design.

Fig. 2 is a side elevation of the same.

Fig. 3 is an end view of the same.

I claim:

The ornamental design for a bumper for ball rolling game device, as shown.

FRANK G. NICOLAUS.
